APPARATUS FOR LIQUID TREATMENT OF
WARPS OF CLOSELY SPACED PARALLEL
RAYON THREADSHans Alwin Schrenk, Arnhem, Netherlands, as-
signor to American Enka Corporation, Enka,
N. C., a corporation of Delaware

Application June 11, 1952, Serial No. 292,920

Claims priority, application Netherlands
July 6, 1951

5 Claims. (Cl. 68—175)

1

The present invention relates to the treatment of threads and more particularly to a liquid aftertreatment of a sheet or warp of closely spaced parallel rayon threads passing in a substantially horizontal plane through an open receptacle filled with a suitable liquid.

When a large number of threads are propelled through a liquid bath in closely spaced parallel relationship, e. g., spaced about 3-7 mm. apart, the adhesion between the liquid and the thread will cause the liquid to flow in the same direction as that of the thread travel. The force of this flow will increase as the distance between the threads decreases and the speed of thread travel increases.

As a result of this phenomena, the flow of liquid is very irregular which adversely affects the physio-chemical properties of the finished thread. Furthermore, the liquid has a tendency to reverse its flow against the end walls of the receptacle whereby it flows in the opposite direction along the bottom and side walls thereof which increases the irregularity of the principal flow and gives rise to still more objectionable varying tensions in the thread.

It is therefore an object of this invention to minimize these objectionable irregular flow characteristics and prevent the liquid from flowing countercurrent to the thread travel in that portion of the receptacle in which the threads move.

A further object of this invention is to provide a liquid treatment receptacle which is peculiarly adapted for effecting a uniform and constant flow of liquid in the direction of thread travel and without any backlash of the liquid at the ends of the receptacle.

Another object of this invention is to conform the width of the receptacle to the width of the sheet of moving threads, i. e., the outermost threads adjacent the respective side walls are never spaced therefrom more than 1 cm.

Other objects and advantages of this invention will become apparent from the following detailed description thereof when considered in conjunction with the accompanying drawings, wherein:

Figure 1 is a plan view of the receptacle constructed in accordance with this invention; and

Figure 2 is a longitudinal vertical section taken on the line 2—2 of Figure 1.

Referring more particularly to the drawings, the numeral 10 represents a flat sheet or warp of parallel threads that are passed to an open treating receptacle generally indicated at 11 by any suitable means such as a system of rollers (not shown).

2

The threads 10 are guided to and around driven rollers 12 and 13 that are partially submerged in an appropriate liquid treating bath 14 which substantially fills the receptacle. The thread path is, therefore, one of substantially vertical entrance and exit to and from the bath while the warp is propelled through the bath in a horizontal direction.

In order to promote an orderly flow of the bath liquid in the direction of thread travel, there is provided an intermediate bottom 15 that extends horizontally of the receptacle slightly below the horizontal plane of the threads and slightly beyond the vertical planes of the threads. 10 This intermediate bottom is supported from the side walls in such a manner as to avoid any disturbance of the flow of liquid therebeneath. Each end of the intermediate bottom 15 is rounded off to form thickened portions at 16 and 17 which promotes a better circulation of the liquid.

Between end wall 18 and thickened portion 16 and between end wall 19 and thickened portion 17, there are disposed a series of generally concentric arcuate shaped baffles 20 and 21 respectively. At each end of the receptacle, each baffle of its respective group, progressively decreases in radius of curvature from the end of the receptacle to the respective end of the intermediate bottom. As shown in the specific embodiment of Figure 2, there are several baffles at each end of the receptacle thereby forming corresponding liquid channels. When the threads 10 are passing in the direction of the upper arrow, the liquid 14 above the intermediate bottom 15 flows in the same direction into and around the baffles 21, into the chamber 22 beneath the intermediate bottom 15 and thence into the baffles 20 and up over the intermediate bottom 15 to complete the cycle and without 25 any backlash against the ends or any disturbing influence around the sides. In order to enhance the liquid flow, the baffles at each end are spaced farther apart at their inlet side than at their outlet side, viz., above the intermediate bottom 15 at the right hand side and below the intermediate bottom at the left hand side as viewed in Figure 2.

Rollers 12 and 13, which may be either positively driven or freely rotatable, are mounted for rotation in U-shaped recessed portions 23—24 and 25—26, respectively. These recesses are formed in double side walls 27 and 28 of receptacle 11 and prevent the threads at the extreme ends from running off the rollers.

55 In the event the warp of threads is not as

wide as the receptacle, a temporary movable partition 29 may be inserted adjacent the outermost threads along one side above the intermediate bottom as shown in Figure 1. Alternatively, two such partitions may be employed at each side of the warp in order to guide the warp down the middle of the receptacle. In this manner the width of the warp always conforms with the effective width of the liquid in the receptacle and the distance between the outermost threads and respective side walls is never greater than 1 cm.

Fresh liquid is supplied through feed line 30 and enters the receptacle through openings 31. The excess liquid flows over spillway 32 and is exhausted through discharge line 33, thereby maintaining a constant liquid level in the receptacle at all times.

It can be seen from the above description that by the use of the present apparatus an extremely uniform flow of liquid in the direction of thread travel can be obtained and turbulence can be reduced to a minimum without resort to a complicated system. In order to promote the flow of liquid beneath the intermediate bottom positive propulsion may be provided in any known manner such as pumps, etc.

What is claimed is:

1. An apparatus for the liquid treatment of a warp of moving threads comprising an open receptacle for containing a liquid, thread guiding rollers disposed in said receptacle, an intermediate bottom below the normal liquid level forming a liquid chamber in the lower portion of the receptacle and a series of generally concentric, arcuate shaped baffles at each end of the receptacle near the respective ends of the intermediate bottom for directing the flow of liquid in a direction concurrent to the direction of thread travel above the intermediate bottom and for directing the flow of liquid in a direction counter-current to the direction of thread travel below the intermediate bottom.

2. An apparatus for the liquid treatment of a warp of moving threads comprising an open receptacle for containing a liquid, thread guiding rollers disposed in said receptacle, an intermediate bottom below the normal liquid level forming a liquid chamber in the lower portion of the receptacle and a series of generally concentric, arcuate shaped baffles at each end of the receptacle near the respective ends of the intermediate bottom and progressively decreasing in radius of curvature from the ends of the receptacle toward the intermediate bottom for directing the flow of liquid in a direction concurrent to the direction of thread travel above the intermediate bottom and for directing the flow of liquid in a direction counter-current to the direction of thread travel below the intermediate bottom.

60

3. An apparatus for the liquid treatment of a moving warp of rayon threads comprising an open receptacle having double side walls provided with recesses, thread guiding rollers disposed in said recesses, an intermediate bottom below the normal liquid level forming a liquid chamber in the lower portion of the receptacle and curved baffles at each end of the receptacle near the respective ends of the intermediate bottom for directing the flow of liquid in a direction concurrent to the direction of thread travel above the intermediate bottom and for directing the flow of liquid in a direction counter-current to the direction of thread travel below the intermediate bottom.

4. An apparatus for the liquid treatment of a warp of moving threads comprising an open receptacle for containing a liquid, thread guiding rollers disposed in said receptacle, an intermediate bottom below the normal liquid level forming a liquid chamber in the lower portion of the receptacle, curved baffles at each end of the receptacle near the respective ends of the intermediate bottom for directing the flow of liquid in a direction concurrent to the direction of thread travel above the intermediate bottom and for directing the flow of liquid in a direction counter-current to the direction of thread travel below the intermediate bottom and a vertical, movable partition adjacent and parallel to the outermost threads at one side of the warp whereby the effective width of the liquid conforms with the width of the warp.

5. An apparatus for the liquid treatment of a warp of moving threads comprising an open receptacle for containing a liquid, thread guiding rollers disposed in said receptacle, an intermediate bottom below the normal liquid level forming a liquid chamber in the lower portion of the receptacle and a series of generally concentric, arcuate shaped baffles at each end of the receptacle near the respective ends of the intermediate bottom, said baffles being spaced farther apart at their inlet side than at their outlet side for directing the flow of liquid in a direction concurrent to the direction of thread travel above the intermediate bottom and for directing the flow of liquid in a direction counter-current to the direction of thread travel below the intermediate bottom.
